W. R. JEAVONS.

OIL HEATER.

APPLICATION FILED FEB. 20, 1913.

1,089,841.

Patented Mar. 10, 1914.

UNITED STATES PATENT OFFICE.

WILLIAM R. JEAVONS, OF CLEVELAND, OHIO.

OIL-HEATER.

1,089,841.

Specification of Letters Patent. Patented Mar. 10, 1914.

Application filed February 20, 1913. Serial No. 749,585.

To all whom it may concern:

Be it known that I, WILLIAM R. JEAVONS, a citizen of the United States, residing at Cleveland, in the county of Cuyahoga and State of Ohio, have invented a certain new and useful Improvement in Oil-Heaters, of which the following is a full, clear, and exact description, reference being had to the accompanying drawings.

10 This invention relates to oil stoves, and more particularly to stoves of the type known to the trade as "heaters" or "lamp stoves." The operation of stoves of this kind has always been attended with the disadvantages that, if the oil level in the font or reservoir becomes too low, there is an insufficient capillary action to the exposed portion of the wick and, as a result, the flame is insufficient in quantity, disagreeable 15 odors are produced, and the wick becomes charred; on the other hand, if the oil level is too high, the capillary action will be too great and the wick will "seep."

20 One of the objects of this invention is to provide a coöperating construction of the parts whereby these two objectionable conditions will be overcome and an odorless flame will be maintained which will burn at substantially full height during the entire period of operation, notwithstanding 25 the different oil levels in the font incident to such operation.

25 In carrying out my invention, I provide a construction whereby the oil level will be positively maintained between two points, (namely below the point of seepage and above the point where the wick will fail to feed sufficiently), which, together with the proper 30 positioning of the parts, will produce a stove or heater free from odors caused by insufficient and excessive oil supply to the burner while the wick life is materially extended.

35 With the foregoing objects in view, the invention may be defined further and more generally as consisting of the combinations of elements embodied in the claims hereto annexed and illustrated in the drawings accompanying and forming part hereof, wherein—

40 Figure 1 represents a central vertical sectional view through the lower portion of a stove or heater constructed in accordance with my invention; Fig. 2, an enlarged sectional view corresponding substantially to the line 2—2 of Fig. 3; and Fig. 3 is a plan

view of the font, the spreader and coöperating parts of the stove frame being removed.

Describing by reference characters the various parts illustrated herein, 1 denotes a 60 stove base having the legs 2.

3 is a heater drum or combustion chamber mounted on a plate 4 which is pivoted to the base, as shown at 5, the bottom 3^a of the drum extending a considerable distance 65 laterally over the font and the plate 4 extending laterally beyond the drum bottom to further embrace the font top.

6 and 7 denote latch members for securing the free or swinging end of the frame 4 to 70 the base. The foregoing parts 6 and 7 may be of any ordinary construction and, in their details, form no part of my invention.

75 Supported within the base frame 1 is the font 70. This font is a shallow metal reservoir having central vertically aligned openings through which extends the outer wick tube 8, said wick tube being soldered or otherwise firmly secured to the edges of these openings, as through the flanges 9 and 80 10. The bottom 11 of the font is slightly inclined downwardly from the periphery toward the central portion thereof and the outer wick tube is provided with openings 12 immediately above this inclined bottom. 85

8^a denotes the inner wick tube and 13 the air distributor, which may be of any desired construction of the type wherein the inner surface and substantially the top of the upper end of the wick are covered or shielded when in operation, as by the sleeve 13^a and flange 13^b, instances of such distributors being shown in my Patents 906,887, issued Dec. 15, 1908, and 964,262, issued July 12, 1910. This distributor and the gallery or collar 13^c are perforated, as is customary, in order to supply air to the flame about the exposed portion of the wick in quantity sufficient to produce a yellow or illuminating flame. In the type of air distributor shown herein, vaporization of oil by the flame occurs mainly at the upper outer portion of the wick, so that the shielded portion of the wick becomes a 90 feeder for the oil to the surface from which the main vaporization occurs, thus insuring a better supply of oil to this surface than would occur if one side and the top of the wick were not so shielded. This construction, together with the coöperating con- 95

100

105

110

struction of the reservoir to be referred to hereinafter, maintains the exposed surface of the wick wet with oil throughout the entire period of operation of the burner, notwithstanding the variations in the height of the oil in the reservoir, with the result that a full flame is produced throughout the entire period of operation and charring of the wick is prevented throughout such period, no matter how prolonged this period may be.

The top of the font is substantially flat and horizontally positioned, being slightly convexed between the periphery and the central aperture, as shown at 7^a. In about the highest portion of this convex surface, the filling opening is located. This filling opening is provided with an inverted frusto conical skirt 14, the upper end whereof depends from a horizontal flange 15 which is connected to the body of the font by a vertical flange 16. The flanges 15 and 16 form a seat for the vertically extending filling casing 17, which may have its upper end bent inwardly and downwardly, as shown at 18, to provide a bearing for the sides of a hollow plug 19, which is preferably of inverted frusto conical shape. This plug is provided with a wire loop 20 whereby it may be conveniently handled. The font is also provided with a gage for indicating the level of the oil therein. This gage comprises generally a float 21 which is rigid with a segment 22 pivoted to a support 23 depending from a hollow metal plug 24. At its lower end, the segment meshes with a pinion 25 on a shaft 26, said shaft being carried by the support 23 and having at its upper end a pointer 27. The gage mechanism is mounted in a casing 28, which is preferably a duplicate of the casing 17, but which is provided, beneath the upper downturned end 29, with a vent opening 30. The lower end of the casing 28 is supported by the flanges 31 and 32 at the upper end of the frusto conical skirt 33, the parts 31 to 33 being substantially identical with the parts 14 to 16, but the flange 32 having a vent opening 34 therein.

It will be observed that the oil font 70 is extremely shallow, compared with its lateral extent, and that the upper ends of the wick tubes project above the upper surface of the oil level that may obtain in said font; also that the lower ends of the wick tubes project below the bottom of this font and that the width of the space between the lower end of the wick tubes is substantially equal to the width of the space between the upper ends of said tubes, whereby a pocket of small oil-holding capacity is provided, which pocket permits the downward excursion of the wick without maintaining a pool of oil of any considerable extent below the bottom of the font. The object of this construction is to maintain the effective oil level between

two points, namely; below the point wherein oversupply or "seepage" will occur, with the production of disagreeable odors, and above the point where the wick will fail to feed a sufficient quantity of oil to maintain a substantially full flame and prevent the charring of the wick as well as the production of disagreeable odors. In operation it has been found that, if the wick has to feed the oil by capillary action a materially greater distance than five inches, the flame will be so low as to produce disagreeable odors and the charring of the wick. Furthermore, if the oil level be less than about an inch and a half below the top of the wick, the wick will overfeed, causing seepage, waste of oil, and the production of noxious odors. By the construction disclosed, the oil is always maintained below the seepage limit and within the capillary limits of the wick, and the oil travels by capillarity, at all times, in sufficient quantity to keep the exposed surface of the wick well supplied. When the oil reaches the lower limit (when the font is empty) the flame quickly goes out, with the production of a minimum of disagreeable odors.

A factor which enhances the results described hereinbefore is the relation of the heated parts to the top of the font, which parts serve to warm the oil in the font to a higher degree than occurs in the ordinary heaters, wherein the effort has been to maintain the oil at as low a temperature as possible,—the temperature of the oil in such ordinary heaters in normal operation being approximately between 90 and 105 degrees F. With the parts arranged as herein described, the temperature of the oil at normal operation ranges from 110 to 140 degrees F., which temperature range practice shows to be absolutely safe while at the same time reducing the viscosity of the oil so that a uniformly ample capillary feed is maintained to the exposed surface of the wick, notwithstanding the lowering of the oil level in the font incident to continued operation.

A further advantage of the wick-tube and font construction resides in the fact that the outer wick tube goes through and connects and anchors the top and bottom of the font and that the wick tubes and the wick and combustion space therebetween are separated from the font, whereby there is no danger of transmission of flame to the interior of the font.

By the construction of filling and gage openings shown herein, the font may be filled to the desired height and the gage inserted and removed without liability of the oil splashing out through the openings. The bottom of the wall or skirt 14 seals the font against the admission of too large a volume of oil thereinto, (the escape of air through the openings 30, 34 being too slow

to interfere with such sealing), controls the upper level of the oil and, by its shape, prevents the oil from splashing out of the opening prior to replacing the plug 19 and also 5 prevents the oil from splashing onto the plug.

Reference has been made to the vent openings 30, 34. These are employed because of the fact that, as the oil is heated up in the 10 operation of the stove, the volume of the oil is increased, which increase in volume would cause the font to overflow through the filling opening unless some means were provided to take care of this increased bulk. 15 The openings 30, 34, however, permit the gradual escape of the air and permit this increase in volume to fill the space occupied by the vented air.

The particular shape of the skirts 14 and 20 34 prevents any oil from splashing into the interior thereof except such as is below the contracted lower ends thereof, while the filling and gage plugs are elevated so far above the oil surface as to protect them against impact under ordinary conditions and incidents of use. The skirts are of such length that, when the font is filled as full as is ordinarily possible, sufficient room is provided in the upper portion of the font to permit the 25 oil to expand without possibility of overflow from such expansion.

Having thus described my invention, what I claim is:

1. In an oil stove, the combination of a 30 font, a pair of wick tubes extending upwardly therefrom, a wick between said tubes, and means for shielding the inner and substantially the top surface of the upper end of the wick, the distance of the top of the 35 wick tubes from the lowest point at which the font communicates with the wick not materially exceeding five inches, whereby the exposed portion of the wick is amply supplied with oil to prevent the charring of such portion, substantially as described.

2. In an oil stove, the combination of a font, a pair of wick tubes extending upwardly therefrom, a wick between said tubes, and means for shielding the inner and 40 substantially the top surface of the upper end of the wick, the distance of the top of the wick tubes from the bottom of the font not materially exceeding five inches, whereby the exposed portion of the wick is amply supplied with oil to prevent the charring of such portion, substantially as described.

3. In an oil stove, the combination of a pair of wick tubes, a wick therebetween, an oil reservoir from which the wick tubes project, the top of said reservoir extending in a horizontal direction from said tubes, means for shielding the inner surface and substantially the top of the upper end of the wick, and a combustion chamber, the bottom 45 whereof extends laterally above the reser-

voir in position to heat the subjacent top of the reservoir, the top of the wick tubes being not materially farther than five inches from the bottom of the reservoir, whereby the oil in the reservoir is warmed sufficiently to reduce its viscosity and enable it to keep the exposed surface of the wick amply wet to prevent charring, notwithstanding the lowering of the oil level in the reservoir, substantially as described.

4. In an oil stove, the combination of a pair of wick tubes, a wick therebetween, an oil reservoir from which the wick tubes project, the top of said reservoir extending in a horizontal direction from said tubes, means for shielding the inner surface and substantially the top of the upper end of the wick, and a combustion chamber, the bottom whereof extends laterally above the reservoir in position to heat the subjacent top of the reservoir, the top of the wick tubes being not materially farther than one and one-half inches from the top of the reservoir, whereby in operation seepage is prevented and the temperature of the oil in the reservoir is maintained at at least 110° F., thereby reducing its viscosity and enabling it to keep the exposed surface of the wick amply wet to prevent charring, notwithstanding the lowering of the oil level in the reservoir, substantially as described.

5. In an oil stove, the combination of a font, a pair of wick tubes extending upwardly therefrom, a wick between said tubes, means for shielding the inner and substantially the top surface of the upper end of the wick, and means for supplying air to the exposed surface of the wick in sufficient quantity to produce an illuminating flame, the distance of the top of the wick tubes from the lowest point at which the font communicates with the wick not materially exceeding five inches, whereby the exposed portion of the wick is amply supplied with oil to prevent charring of such portion, substantially as described.

6. In an oil stove, the combination of a font, a pair of wick tubes extending upwardly therefrom, a wick between said tubes, and means for shielding the inner and substantially the top surface of the upper end of the wick, the distance of the top of the wick tubes from the bottom of the font not materially exceeding five inches and the distance of the top of the wick tubes from the top of the font not materially exceeding one and one-half inches, whereby seepage is prevented and the exposed portion of the wick is amply supplied with oil to prevent the charring of such portion, substantially as described.

7. In an oil stove, the combination of a pair of wick tubes, a wick therebetween, an oil reservoir from which the wick tubes project, the top of said reservoir extending

1. in a horizontal direction from said tubes, means for shielding the inner surface and substantially the top of the upper end of the wick, and a combustion chamber the bottom 5 whereof extends laterally above the reservoir in position to heat the subjacent top of the reservoir, the distance of the tops of the wick tubes from the top of the reservoir not materially exceeding one and one-half 10 inches and the distance of the tops of said tubes from the lowest point at which the reservoir communicates with the wick not materially exceeding five inches, whereby seepage is prevented and the oil is warmed 15 sufficiently to reduce its viscosity and enable it to keep the exposed surface of the wick amply wet to prevent charring, notwithstanding the lowering of the oil level in the reservoir, substantially as described.
2. 8. In an oil stove, the combination of a pair of wick tubes, a wick therebetween, an oil reservoir from which the wick tubes project, the top of said reservoir extending in a horizontal - direction from said tubes, 20 means for shielding the inner surface and substantially the top of the upper end of the wick, means for supplying air to the exposed surface of the wick in sufficient quantity to produce an illuminating flame, and 25 a combustion chamber the bottom whereof extends laterally above the reservoir in position to heat the subjacent top of the reservoir, the distance of the tops of the wick tubes from the top of the reservoir not materially exceeding one and one-half inches 30 and the distance of the tops of said tubes from the lowest point at which the reservoir communicates with the wick not materially exceeding five inches, whereby seepage is 35 prevented and the oil is warmed sufficiently to reduce its viscosity and enable it to keep the exposed surface of the wick amply wet to prevent charring, notwithstanding the lowering of the oil level in the reservoir, 40 substantially as described.
3. 9. In an oil stove, the combination of a font having a top and a bottom, wick tubes projecting through and above the top and below the bottom of the font, a wick between said tubes, and means for shielding the inner surface and substantially the top of the upper end of the wick, the distance of the bottom of the font from the top of the wick tubes being not materially greater than five inches, and said tubes communicating with said font, the bottom portion of the wick tubes being of substantially the same width as the upper portion, whereby such bottom portion provides a pocket of small oil-holding capacity to permit the downward excursion of the wick and whereby the exposed portion of the wick is amply supplied with oil to prevent the charring of such portion, substantially as described.
4. 10. In an oil stove, the combination of a font having a top and a bottom, wick tubes projecting through and above the top and below the bottom of the font, a wick between said tubes, and means for shielding the inner surface and substantially the top of the upper end of the wick, the distance of the bottom of the font from the top of the wick tubes being not materially greater than one and one-half inches, the bottom portion of the wick tubes being of substantially the same width as the upper portion, whereby such bottom portion provides a pocket of small oil-holding capacity to permit the downward excursion of the wick and whereby the exposed portion of the wick is amply supplied with oil to prevent the charring of such portion, substantially as described.
5. 11. In an oil stove, the combination of a font having a top and a bottom, wick tubes projecting through and above the top and below the bottom of the font and communicating with said font, the bottom portion of the wick tubes being of substantially the same width as the upper portion whereby a pocket of small oil holding capacity is provided to permit the downward excursion of the wick, a wick between said tubes, a combustion chamber having its bottom extending laterally above the font in position to heat the subjacent top of the font, and means for shielding the inner surface and substantially the top of the upper end of the wick, the distance of the top of the font from the top of the wick tubes being not materially greater than one and one-half inches and the distance of the bottom of the font from the top of the wick tubes being not materially greater than five inches, whereby seepage is prevented, the oil is warmed sufficiently to reduce its viscosity, and the exposed portion of the wick amply supplied with oil to prevent the charring of such portion, substantially as described.
6. 12. In an oil stove, the combination of a font having a top and a bottom, wick tubes projecting through and above the top and below the bottom of the font and communicating with said font, the bottom portion of the wick tubes being of substantially the same width as the upper portion whereby a pocket of small oil holding capacity is provided to permit the downward excursion of the wick, a wick between said tubes, a combustion chamber having its bottom extending laterally above the font in position to heat the subjacent top of the font, means for shielding the inner surface and substantially the top of the upper end of the wick, and means for supplying air to the exposed surface of the wick in sufficient quantity to pro-

duce an illuminating flame, the distance of the top of the font from the top of the wick tubes being not materially greater than one and one-half inches and the distance of the 5 bottom of the font from the top of the wick tubes being not materially greater than five inches, whereby seepage is prevented, the oil is warmed sufficiently to reduce its viscosity, and the exposed portion of the wick amply

supplied with oil to prevent the charring of 10 such portion, substantially as described.

In testimony whereof, I hereunto affix my signature in the presence of two witnesses.
